UNITED STATES PATENT OFFICE.

GIUSEPPE DI PIETRO MARTIRE, OF MILAN, ITALY.

IGNITION-MAGNETO SWITCH FOR INTERNAL-COMBUSTION ENGINES.

1,308,503.

Specification of Letters Patent.

Patented July 1, 1919.

Application filed May 21, 1918. Serial No. 235,841.

To all whom it may concern:

Be it known that I, GIUSEPPE DI PIETRO MARTIRE, subject of the King of Italy, resident of Milan, in the Kingdom of Italy, have invented new and useful Improvements in Ignition-Magneto Switches for Internal-Combustion Engines, of which the following is a specification.

The present invention has for its object a switch specially adapted for actuating one or more internal combustion engines by means of either or both of two ignition magnetos during the ordinary running of the engines, the starting of one or more of the engines being eventually effected by a single ignition magneto, and each engine and each magneto being independently operated.

Figures 1 to 4 in the annexed drawing illustrate by way of example one mode of execution for the case of two engines capable of being started independently with a single starting magneto; the construction however can be adapted to any number of engines. It is further understood that the constructional and form details may be varied from those described and illustrated without departing from the spirit and scope of the invention.

30 Fig. 1 is a front view.

Fig. 2 is a cross section.

Fig. 3 is an internal view of the device as seen looking toward the cover.

Fig. 4 is an internal view of the device as seen looking toward the base.

Fig. 5 shows in section a simplified form applicable when the apparatus has to work as an interrupter instead of as a change-over switch.

40 Fig. 6 is a section on the line 6-6 in Fig. 5.

Figs. 7 and 8 illustrate in section and plan a modified change-over construction with the buttons arranged in a straight line over a plate that can be moved endwise.

In the construction according to Figs. 1 to 4 the leads from the starting magneto are connected to $-m-$, and the leads from the ignition magnetos I-II are connected to 50 the terminals c_1-c_2 .

A is a lever by means of which the contact member $-t-$ can be brought into contact with the buttons M_1-M_2 and the starting magneto (which is connected to $-m-$) can 55 be connected up to one or the other of the two engines. The button $-r-$ serves to

insert, by means of a spring changeover switch t_1 of well known construction, a battery of storage cells in lieu of the starting magneto. A spring $-u-$ fitted to the lever A and a segment $-v-$ provided with notches or stops serve to lock the lever A in position.

For each engine a set of buttons z_1 , respectively z_2 is provided, these buttons constituting multiple commutators for connecting up the respective engine to either or both of its ignition magnetos. When in either set the button z_1 or z_2 bearing the double figure (1-2) is depressed, both magnetos I and II 70 of the corresponding engine are set into operation. When button 1 is depressed, the magneto II is disconnected and only the magneto I remains in operation. When button 2 is depressed, the magneto II is connected up and the magneto I disconnected. When button 0 is depressed, both magnetos are disconnected and the engine is stopped.

In order to automatically release the button or buttons previously depressed—and therewith break the connections established by the same—when any other button is depressed, a disk D adapted to swing on its spindle is provided for each set of buttons. All around the periphery of each disk a 85 number of holes is formed equal to the number of buttons of the respective set. In these holes are apt to slide the conical portions $-g-$ of the contact spindles $-s-$, the larger bases of the cones $-q-$ equaling the 90 holes in diameter. Each disk D is spring-loaded, the spring causing the holes always to bear against the spindles $-s-$ and therewith to lie eccentrically in relation to the cones $-q-$. The contact half-rings h_1-h_2 95 are connected to the terminals $-c_1-c_2-$ by $-f_1-f_2-$ on one side and to the contact members of the buttons 1 and 2 by g_1-g_2 on the other side. The button (1-2) makes a direct contact with the half-rings through 100 the cones $-q-$. The spindle corresponding to the button 0 makes no contact, and each spindle is placed under the action of a spring tending to force it outward.

When any of the buttons is depressed, the corresponding cone enters a disk hole and, due to its eccentricity, causes the disk to swing through a certain angle, after which the disk-spring brings the disk back into contact with the spindle and locks the spindle in the new position, the spindle being thus prevented from moving outward of the

hole and the contact established by the same being thus maintained.

Later, when any other button is depressed, the disk is swung again through a certain angle, whereby the hole corresponding to the button previously depressed is brought to lie concentrically to the corresponding cone; this latter is accordingly allowed to spring outward of the hole and to break the former contact, while the connection established through the latest button operation is rendered permanent.

By depressing the button 0 all other contacts are broken without establishing any new one.

The operations of the various magnetos and motors as well as the trip gear for the break of the contacts are entirely independent from one another, and the buttons can be operated in any sequence whatever without any preestablished order.

When it is only the question of establishing the connection between the starting magneto and the engine, a simpler form of the device can be adopted as shown in Figs. 5 and 6. The motor is connected to M and the starting magneto to $-m-$. The two buttons z_3-z_4 , by means of cones q_4 , actuate a swinging plate $-p-$, which is placed under the action of springs $-j-$ in such a way that the opposite sides of the holes $-o-$ formed in the plate $-p-$, due to the springs $-j-$, are caused to bear against the button spindles $-s-$ and to lie eccentrically in relation to the spindle cones $-q_3-q_4$. When $-z_3-$ is depressed, the opposite end of the corresponding spindle operates a lever $-l-$ electrically connected to $-m-$ and causes it to make contact with M , this contact being maintained until the button z_4 is depressed, thereby in consequence of the swing of $-p-$, the cone $-q_3-$ being released and the contact broken.

Figs. 7 and 8 illustrate a similar device with buttons $-z_4-$, in any number whatever, arranged in a straight line and coöperating with a plate $-w_1-$, fitted with holes $-x-$ which, by a spring $-y-$, are normally held against the spindle $-s_0-$.

When a button is depressed, the plate w_1 is

moved endwise and the cone corresponding to the depressed button gets through and past the corresponding plate-hole, while any other spindle whose cone happens to lie below the opposite face of the plate is suddenly drawn upward by a spring with which each spindle is fitted. In this way a change-over can be effected among any number of lines, two by two.

Having now described my invention and how the same is to be carried into practice, what I desire to protect by Letters Patent is:

1. The combination with a plurality of ignition magnetos for internal combustion engines, of a switch comprising a lever with which the engines are started in succession through a single starting magneto, and a contact-button disk for each motor, by means of which disks each motor is connected up to one or the other or both of its ignition magnetos, each contact-button actuating a spindle fitted with a cone adapted to slide in a hole formed in the disk, and each disk being loaded by a spring that tends to maintain the disk holes eccentrically relatively to the spindle cones so that, when a contact-button is depressed and the corresponding spindle and cone move axially, the disk swings through a certain angle and lets the cone of the actuated spindle pass through the corresponding holes and allows the spindles of the buttons previously depressed to spring back.

2. Ignition magneto switch for interrupting the ignition circuit of an internal combustion engine, comprising a plate adapted to swing about its pivot under the action of a spring and fitted with holes at each end, two buttons adapted to coöperate with the said holes, each button actuating a spindle fitted with a cone for the purpose of swinging the plate when the cone passes through the corresponding disk hole and of preventing the button's return, while either button releases the other, and a contact plate actuated by one of the said buttons, substantially as described and illustrated.

In testimony thereof I affix my signature.
GIUSEPPE DI PIETRO MARTIRE.
